MECHANICALLY DRIVEN PERCUSSIVE TOOL

Filed Dec. 4, 1924

Patented Mar. 30, 1926.

1,578,275

UNITED STATES PATENT OFFICE.

ROBERT WILLIAM JOHNSTON FLETCHER, OF EDINBURGH, SCOTLAND.

MECHANICALLY-DRIVEN PERCUSSIVE TOOL.

Application filed December 4, 1924. Serial No. 754,001.

To all whom it may concern:

Be it known that I, ROBERT WILLIAM JOHNSTON FLETCHER, a subject of the King of England, residing at Edinburgh, Midlothian, Scotland, have invented certain new and useful Improvements in Mechanically-Driven Percussive Tools, of which the following is a specification.

This invention is for improvements in or relating to mechanically driven percussive tools of the type comprising a rotary driving member, a spring-controlled reciprocating driven member and an operative connection between the rotary driving and reciprocating driven members, a cam element and a co-operating abutment element in operative engagement with each other, one of which elements is rotated by said driving member and one of which is moved relatively to the other to reciprocate the driven member.

The invention has for one of its objects to improve tools of this type and to produce a construction which is simple to manufacture and efficient in operation. Another object is to convert some or all of the friction between the cam and its abutment to rolling friction, at the same time permitting the reciprocating member to have a sharp unhindered working stroke. It is also an object of the invention to overcome difficulties hitherto caused by the inertia of moving parts and render it possible always to keep the tool-bit in contact with the work. It is an additional object of the invention to provide an improved construction of mechanism for converting rotary into reciprocatory motion which can be operated at a high speed with a rapid snap action of the reciprocated member.

For a more complete understanding of the invention there will now be described, by way of example only and with reference to the accompanying drawings, one constructional form of percussive tool according to the invention. It is to be understood, however, that the invention is not restricted to the precise constructional details set forth.

In these drawings:—

Figure 1 is a longitudinal section through the tool, showing the parts in working position.

Figure 2 is a like view showing the driving clutch disengaged.

Figure 3 is a perspective detail view of the operating cam, and

Figure 4 is a similar view of a detail of the tool which co-operates with the cam.

Like reference numerals indicate like parts throughout the drawings.

The tool body or casing 10 is of tubular formation having an enlarged end 11. Its other end is bored to receive a holder 12 for the tool-bit. This holder is retained in position by a detachable cap 13 and it can be arranged to receive any desired form of tool-bit such as a hammer head, chisel or other implement chosen according to the work, such for instance as stone dressing, to be performed by the tool. A clearance is shown at 14 and it will be understood that consequently the holder 12 is permitted to take a certain amount of endwise movement inside the tool body 10. Its upward movement, however, is limited by the shoulder 15 and its downward movement by the cap 13. When the tool-bit is held pressed against the work, the upper face 16 of the holder 12 will stand above the face 17 in the tool body and in this way the holder is adapted to serve as an anvil to sustain blows from a reciprocating driven member 18. The upper face 16 of the holder need only project a very slight distance above the face 17 so that the latter can be arranged to exert a positive stop to the downward movement of the member 18 after the blow has been struck and the holder 12 consequently caused to withdraw below the face 17.

The enlarged end 11 of the tool body is received inside the hollow end 19 of a handle 20 which extends in axial alignment with the tool body and has at its further end a socket 21 for connecting to a flexible shaft casing not shown. The overlapping parts 11 and 19 are connected together by screws 22 in the tool body and washer plates 23 around the heads of the screws working in elongated slots 24 in the hollow end of the handle. These slots permit the handle to have a certain amount of movement longitudinally of the tool body. Mounted within the interior of the handle is a spindle 25 whereof the end 26 is intended to be connected to the flexible shaft whereof the casing is received in the socket 21. The other end of the spindle 25 is engaged by a ball 27 which is pressed by a spring 28 in such a direction as to tend to push the handle along the tool body in the opposite direc-

tion to that in which pressure is applied by the handle to hold the tool against the work. When such pressure is being applied by hand the pressure of the spring 28 will 5 be overcome, but as soon as the hand pressure is relaxed the spring 28 will function to move the handle relatively to the tool as just described.

The relative longitudinal movement of the 10 handle and tool body is utilized to cause engagement and disengagement between the two parts of a dog clutch. One of these parts, namely the part 29 is carried on the spindle 25 against a bearing 30, and this part 15 29 is the driving member of the clutch. The other part 31 of the clutch is carried in a bearing in the tool body which will be described below, and the interior of the clutch part 31 is utilized to house the lower end 32 20 of the spindle 25, this being the end against which the ball 27 is pressed. From the foregoing it will be understood that when the tool is being pressed against the work, the parts of the clutch will be brought into engagement with each other, but when such 25 pressure is relaxed, the spring 28 will move the clutch parts out of engagement with each other.

The enlarged end 11 of the tool body has 30 its mouth closed by a cap 33 which is recessed to receive a bearing 34, and passing concentrically through this bearing is an extension 35 from the clutch part 31. This extension 35 houses the spring 28 and it constitutes 35 the rotary driving member referred to at the commencement of this specification. Its lower end is received within the interior of the upper end of the reciprocating member 18 and is splined to the latter, as at 36, 40 so that the member 18 will partake of its rotary movement while being free to reciprocate.

The reciprocating member 18 takes the 45 form of a hollow sleeve with a closed lower end which reaches down into the interior of the smaller part of the tool body 10. In the interior of the sleeve is situated a controlling spring 37 which is the propelling medium causing the sleeve to strike the holder 12.

50 The spring is received between the closed lower end of the reciprocating member 18 and the lower end 38 of the extension 35 of the clutch part 31 and is preferably permanently in compression. The upper end of 55 the reciprocating member 18 has an external enlargement 39 constituting a cam element the lower face of which is formed as a cam surface annularly arranged about the axis of the tool body. This cam surface is directed 60 towards a co-operating abutment element constituted by a shoulder 40 in the interior of the tool body. As the parts rotate, the effect of the cam is to cause the reciprocating member 18 to be intermittently drawn 65 away from the holder 12, thereby intermit-

tently compressing the spring 37 and releasing it so as to cause the member 18 to strike the holder 12. The cam surface may conveniently have two downwardly directed peaks 41 and 42, the slope on the one side 70 of each peak being gradual and on the other side being abrupt (see particularly Figure 3) so that the withdrawal of the member 18 from the holder 12 may be gradual and its release towards the holder 12 sharp and unhampered. The abutment 40 carries a ring 43 which is formed with two pockets for balls 44 situated at opposite ends of a diameter. The pockets are illustrated in detail in Figure 4 and it will be seen that one of the 75 balls 44 has been omitted from that figure for the sake of clearness. In the construction illustrated each pocket comprises an outer wall 45 and an inner wall 46, these walls being concentric with the axis of the 80 tool body and the adjacent faces in each pair of walls are of concave formation, as at 47, to correspond with the shape of the balls 44. The concave formation does not extend completely throughout the length of the 85 walls 45 and 46, but shoulders 48 constituting stops are formed at one end of each pocket. The concave formation, however, extends completely to the other ends of the 90 pockets, and near these latter ends, stops in 95 the form of studs 49 are fitted in the ring 43. Each ball 44, therefore, can roll in its pocket between the two concave faces, its progress at the one end being limited by the stop 49 and at the other end by the shoulders 48. It will be seen that the upper face of each pocket is completely open and the balls 100 are intended to be held in their respective pockets merely by engagement with the surface of the cam which, it will be appreciated, is drawn towards the balls by the pressure of the spring 37. Referring now to Figure 105 3, the gradually sloping faces of the cam are shown as being provided with grooves 50 to correspond to a portion of the contour 110 of the balls 44, and the abruptly sloping faces of the cam with corresponding grooves 51. The balls are thus permitted a controlled translatory movement between the cam 39 and the ring 43 relatively to the driving member 35 and the driven member 18 in the same direction as and also in the opposite direction to that of the rotary movement of the cam 39.

In operation, the spindle 25 with the 115 clutch part 29 will rotate idly until the operator presses the tool against the work. This will cause the two clutch parts 29 and 31 to engage each other whereupon the rotation of the spindle 25 will be communicated to the cam. The ring 43 carrying the balls 44 is stationary and consequently as the peaks of the cam ride over the balls the member 18 will be reciprocated. It will be 120 slowly drawn back away from the tool-bit 125 130

holder 12 and allowed abruptly to move towards the latter to strike the blow. The balls 44 will travel bodily in the recesses 50 and 51 in the cam face and the abruptness 5 of the blow will be increased by reason of the fact that the balls are shot along their pockets out of the way of the peaks of the cam. The stops 48, 49 positively control the 10 end positions of the balls in relation to the cam, and they ensure that whenever the hammer action occurs the relative position of the cam 39, balls 44 and ring 43 shall always be the same.

It is, of course, not essential to employ two 15 balls nor to employ a cam with two peaks as any suitable number may be employed. Similarly, rollers may be substituted for balls and instead of the ball being carried in a pocket on the face of a flat abutment 20 it could be carried by the cam. The cam may be detachable so as to be readily replaceable and the controlling spring for the reciprocating member may encircle it instead of being housed in its interior. The balls or 25 rollers may be carried by the reciprocating member and the cam affixed to the body of the tool or the reciprocating member may have axial movement only and the cam or co-operating abutment may be arranged to be 30 rotated. The construction may also be modified in other ways without departing from the spirit and scope of the invention.

I claim:-

1. In a tool of the character described, the 35 combination of a casing, a rotatable driving member journaled therein, a reciprocatory driven member capable of longitudinal movement in the casing, a cam element and a cooperating abutment element, an anti-friction bearing member between the said 40 elements, one of which elements is rotatable in relation to the other and is arranged to be rotated by said driving member, and one is arranged to move in a direction towards and 45 away from the other and to reciprocate said driven member, which bearing member is permitted a controlled translatory movement between said elements relatively to said driving and driven members in the same direction as and also in the opposite direction to 50 that of the rotary movement of the movable element, and stops fixed on one of said elements and arranged to limit the movement of said bearing member in each direction 55 of travel whilst permitting it to move bodily between the stops in relation to said elements, substantially as described.

2. In a tool of the character described, the 60 combination of a casing, a rotatable driving member journaled therein, a reciprocatory driven member capable of longitudinal movement in the casing, a cam element and a 65 cooperating abutment element, an anti-fric-

tion bearing member between the said elements, one of which elements is rotatable 65 in relation to the other and is arranged to be rotated by said driving member, and one is arranged to move in a direction towards and away from the other and to reciprocate said driven member, a pocket of elongated 70 part-circular shape in the face of said abutment element for receiving said bearing member, and stops fixed on the abutment element and arranged to limit the movement of said bearing member in said pocket in each direction of travel whilst permitting it to move bodily between the stops in relation to said elements, substantially as described.

3. In a tool of the character described, the combination of a casing, a rotatable driving member journaled therein, a reciprocatory driven member arranged to be rotated by the driving member and to move longitudinally relatively thereto, a cam element carried by 80 said driven member and a cooperating abutment element fixed on the casing, a spring acting on said driven member and tending to press the cam element against said abutment element, balls between said elements, which balls are permitted a controlled translatory movement about the axis of rotation of said cam element, and a plurality of stops, two for each ball, fixed on said abutment element and arranged to limit the movement 85 of said balls in each direction whilst permitting each ball to move bodily between its two stops in relation to said elements, which stops are so arranged as to ensure that whenever the driven member is impelled under 90 the action of its spring the relative position of said cam element, balls and abutment element shall always be the same, substantially 95 as described.

4. In mechanism for converting rotary into reciprocatory motion, the combination 100 of a cam element and a cooperating abutment element, whereof one is rotatable in relation to the other and one is arranged to reciprocate in a direction towards and away 105 from the other, anti-friction bearing members between said elements, which bearing members are permitted a controlled translatory movement about the axis of rotation of the rotatable element, and stops fixed on 110 said abutment element and arranged to limit the movement of said bearing members in each direction of travel whilst permitting them to move bodily each between two stops 115 in relation to said elements, driving means for rotating the rotatable element, and a driven member arranged to be reciprocated 120 by the reciprocatory element, substantially as described.

In testimony whereof I affix my signature.

ROBERT WILLIAM JOHNSTON FLETCHER.
